Primary Examiner — Raphael Barkai*(74) Attorney, Agent, or Firm* — Alston & Bird LLP(57) **CLAIM**

I claim the ornamental design for an eyewear, as shown and described.

DESCRIPTION

FIG. 1 is a perspective view of the eyewear, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof, the right side elevation being a mirror image; and,

FIG. 7 is a side elevation cross-section view thereof, taken along the line 7-7 in FIG. 4.

The broken lines are directed to environment and are for illustrative purposes only. The broken lines form no part of the claimed design.

1 Claim, 6 Drawing Sheets*FIG. 1*

FIG. 2

FIG. 3

FIG. 4

FIG. 5
